DAVID L. PEACOCK, OF ROCKPORT, INDIANA.

Letters Patent No. 73,116, dated January 7, 1868.

IMPROVEMENT IN SHINGLE-MACHINES.

The Schedule referred to in these Letters Patent and making part of the same.

TO ALL WHOM IT MAY CONCERN:

Be it known that I, DAVID L. PEACOCK, of Rockport, in the county of Spencer, and State of Indiana, have invented a new and improved Shingle-Machine; and I do hereby declare the following to be a full, clear, and exact description of the same, reference being had to the accompanying drawings, forming part of this specification, and in which—

Figure 1 represents a perspective view of the cutter-frame M.

Figure 2 is a front elevation of my invention.

Figure 3 is a rear elevation of the same.

Figure 4 is a longitudinal vertical section of the same.

Similar letters of reference indicate corresponding parts in the several figures.

In this invention the shingle is split from a block, and planed while passing through the machine.

In order that others skilled in the art to which my invention appertains may be enabled to make and use the same, I will proceed to describe it in detail.

In the drawings, A A represent the bed-pieces, B B the posts or legs, C C the frame, and D D the boxes in which the shingle-bolts are held while the shingles are being cut from them. E is a shaft, bearing on each end a pulley, e, from which a belt works the lower planer by means of the pulley f. F is the lower planer, provided with knives, a a, and running in fixed boxes in the frame C. The upper planer G runs in bearings in the end of two arms, H H, pivoted to the frame C at h, and capable of rising and falling with the arms H H. The latter carry a roller, I, just behind the planer G, bearing in boxes which have a vertical sliding motion in slots in the arms H H. The shaft of the planer G has a pulley, g, on each end, to which motion is communicated by a crossed belt from the lower planer-shaft. b is a screen in front of the upper planer G. Just beneath it, and in front of the upper planer, is a roller, K, similar in construction to the roller I, working also in boxes having a vertical sliding motion in slots in the inside of the frame C. The inner sides of the frame C are each provided with two parallel longitudinal grooves or channels, L L, which support and guide the sliding cutter-frame M. The latter is composed of two plates, m and m', attached together by the blocks m'', to which they are bolted. In an aperture in the upper plate m the cutting-knife K is fixed—a knife straight on its upper and bevelled on its under side. The upper side of the plate m, in front of the cutting-knife N, is cut down, so that the bolt resting upon it will come in contact with the edge of the knife. The under plate m' has a raised bed, m''', upon which the shingle falls after being cut from the bolt. The forward end of the under plate terminates in two arms, t t, projecting forward at each side, and bevelled down to a sharp edge, the purpose of which is to run under the ends of the arms H H, which have their lower corners slightly bevelled off, to insure the sliding of the plate m' under them, whereby the planer G is gradually raised as the cutter-frame M advances towards it. O is a beam, which just grazes the upper surface of the bed m''' as the cutter-frame is slid forward and back in its guiding-grooves. P is a flat floor in front of the planers, extending about to the middle of the machine. The plate m' slides back and forth upon this floor, its forward end, between the arms that push up the planer; as before described, being cut square, as shown at r, so as to push along whatever may be lying upon the floor P as the cutter-frame advances.

The operation of a machine thus constructed is as follows: The bolt is placed in the box D, its side down. The cutter-frame is then adjusted in the grooves L L and slid forward, when the knife N comes in contact with the lower side of the bolt and cuts or splits a shingle therefrom, which is forced through the aperture in front of the knife N, and falls upon the raised bed m''' in the lower plate of the cutter-frame. The cutter-frame is then drawn back for a new cut, the beam O preventing the shingle from being carried back with it, and sliding the shingle forward upon the frame until it drops off of the bed m''' upon the plate at m'''. By this time a new shingle has fallen upon the bed m''', which in its turn pushes the first shingle forward entirely off of the sliding frame upon the floor P. As the frame is again drawn back and forth, a third shingle falls upon the bed m''', and, in connection with the second shingle, pushes the first shingle between the planers. The shoulders s and r assist the rear shingles in pushing the forward ones towards the planers. The bed m''', the part m''', and the floor P in front of the shoulder r, when the sliding frame is drawn back, must each carry one shingle.

forward endways. The arms upon the forward end of the plate m' must be bevelled just so much as is necessary in order to cause the planer G to give the proper bevel to the shingle.

I do not broadly claim a sliding cutter-frame, holding a knife, and operating in connection with a box holding the bolts; but

What I do claim as my invention, and desire to secure by Letters Patent, is—

1. A cutter-frame, composed of two parallel plates $m\ m'$, the upper one holding a knife, N, and the lower one having a raised bed, m''' , arranged and combined substantially as and for the purpose specified.

2. The combination of a cutter-frame, having tapering arms $t\ t$, with the movable planer G, bearing in hinged arms H H, substantially as and for the purpose specified.

DAVID L. PEACOCK.
